(57) **CLAIM**

The ornamental design for an art display reinforcing member, as shown and described.

DESCRIPTION

FIG. 1 is an exploded isometric view of an art display reinforcing member (with one of the longitudinal flaps thereof being shown, for clarity, angularly offset from the transverse flaps) including release liners along the sides, and an art display that is to receive the art display reinforcing member; FIG. 2 is a top view of the art display reinforcing member in position within the art display, with all flaps shown flat against the art display;

FIG. 3 is a front view of the art display reinforcing member shown in FIG. 2, which is a mirror image of the back view (not shown);

FIG. 4 is a left side view of the art display reinforcing member shown in FIG. 2, which is a mirror image of the right side view (not shown); and,

FIG. 5 is a bottom view of the art display reinforcing member shown in FIG. 2.

The even-broken lines in FIG. 1 illustrate release liners that are removable from the art display reinforcing member and form no part of the claimed design. The dot-dash-dot lines illustrate an art display that is to receive the art display reinforcing member and form no part of the claimed design.
